(57) **CLAIM**

The ornamental design for an infrared camera, as shown and described.

DESCRIPTION

FIG. 1 is a front elevation view of an infrared camera embodying my new design with a display in a closed configuration; FIG. 2 is a rear elevation view thereof with the display in a closed configuration;

FIG. 3 is a top plan view thereof with the display in a closed configuration;

FIG. 4 is a bottom plan view thereof with the display in a closed configuration;

FIG. 5 is a left elevation view thereof with the display in a closed configuration;

FIG. 6 is a right elevation view thereof with the display in a closed configuration;

FIG. 7 is a rear-left perspective view thereof with the display in a closed configuration;

FIG. 8 is a front-left perspective view thereof with the display in a closed configuration;

FIG. 9 is a rear elevation view thereof with the display in an open configuration;

FIG. 10 is a right elevation view thereof with the display in an open configuration;

FIG. 11 is a front elevation view thereof with the display in an open configuration;

FIG. 12 is a left elevation view thereof with the display in an open configuration;

FIG. 13 is a front-left perspective view thereof with the display in an open configuration; and,

FIG. 14 is a rear-left perspective view thereof with the display in an open configuration.

The broken lines depict portions of an infrared camera in which the design is embodied and form no part of the claimed design.

1 Claim, 14 Drawing Sheets
